UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

ORE-CAR.

1,400,866.

Specification of Letters Patent. Patented Dec. 20, 1921.

Application filed July 12, 1920. Serial No. 395,507.

To all whom it may concern:

Be it known that I, ARGYLE CAMPBELL, a citizen of the United States, residing at Chicago, in the county of Cook and State of Illinois, have invented a certain new and useful Improvement in Ore-Cars, of which the following is a full, clear, concise, and exact description, reference being had to the accompanying drawings, forming a part of this specification.

This invention relates to improvements in ore cars.

One object of the invention is to provide an ore car of not greater than the standard over-all dimensions having a greater load-carrying capacity than present types of ore cars of similar over-all dimensions.

Other objects of the invention are to provide an ore car having a large single discharge opening; having the hopper sides and ends so arranged as to render the car self-clearing; to provide an ore car having unusual strength to resist buffing and pulling shocks; and to provide an ore car having greater capacity than any heretofore having similar over-all length and width dimensions.

One specific object of the invention is to provide an ore car adapted for the usual ore-carrying traffic and wherein is provided a single hopper with the side and end walls of the hopper so sloping and conformed as to eliminate any crowding of the ore as it is being unloaded, or abrupt restriction of the passage for the ore as it moves toward the discharge opening.

This application constitutes a continuation, in part, of my prior pending application 386,543 filed June 4, 1920.

As is well known to those skilled in the art, so-called ore cars are chiefly employed in the transporting of ore to large docks where the ore is discharged into bins spaced twenty-four feet apart from center to center, the bins in turn being arranged to discharge into ore-carrying steamers. In this class of traffic, it is essential that all ore cars composing the trains be of standard length which has been made twenty-four feet from coupler center to coupler center or substantially twenty-two feet over-all from striking plate to striking plate. The standard width of such ore cars, over-all is eight feet eleven inches or nine feet and the car which I have invented and which is disclosed herein con-

forms to said standard over-all and width dimensions. In the said ore-carrying trade, it is the general practice to provide ore bins of substantially three hundred tons capacity and in order to facilitate records and calculate the percentages of different ores or classes of ores dumped into the bins, it has been the general practice to make the ore cars of fifty tons normal capacity and sixty tons capacity when heaped or overloaded to the limit so that an even multiple of car loads, six or five, is required in filling a single bin. By carrying out my improvements and still remaining within the standardized over-all dimensions now employed, I have increased the capacity of the car without any appreciable extra metal or weight or cost of manufacture to a normal capacity of seventy tons and a moderately heaped or overloaded capacity of seventy-five tons. With this arrangement, it is evident that four car loads where my improved cars are employed are only required as against the five or six car loads heretofore with consequent decrease in transportation charges and greater speed in transporting a given quantity of ore.

In the drawings forming a part of this specification, Figure 1 is a side elevation of an ore car embodying my improvements, the over-all length of which, from striking plate to striking plate, is made twenty-two feet. Fig. 2 is a central longitudinal sectional view of the car shown in Fig. 1 upon a larger scale, the length of the section being approximately two-thirds the full length of the car. Fig. 3 is a part top plan view, part horizontal section of the car illustrated in Fig. 1, the section corresponding to the line 3—3 of Fig. 1. Fig. 4 is an end elevation of the improved ore car and on a scale corresponding to Fig. 2. Fig. 5 is a transverse partial sectional view corresponding substantially to the line 5—5 of Fig. 1, the section being on a scale corresponding to Figs. 2 and 4. Fig. 6 is a sectional view similar to Fig. 5 but taken on the line 6—6 of Fig. 1. Fig. 7 is a transverse sectional view upon the same scale as Figs. 2, 4, 5 and 6 and taken on the line 7—7 of Fig. 1. In Fig. 7, one of the hopper doors is shown by dotted lines in its open position. And Fig. 8 is a plan view of a special combined reinforcing member and baffle plate employed along the bottom edge of the end hopper walls.

In carrying out my invention, I leave the single discharge opening entirely unobstructed and, as will be appreciated by those skilled in the art, it is necessary to omit any center 5 sills at this part of the car in order to obtain such a clear opening. To compensate for the omission of the usual center sills of the car underframe, I have provided a novel 10 type of underframe and load-carrying structure as follows. The structure at each end of the car is the same so that a detailed description of one end will suffice.

At each end of the car, I provide a heavy casting designated by the reference A, said 15 casting having a relatively short bolster formed integrally therewith. Said bolster includes a body bolster center plate 10 and laterally extended arms 11—11, said arms being strengthened on the top thereof by 20 flanges 12—12. Also formed integrally with the casting A are draft sills 13—13 extended outwardly from the center plate 10, said draft sills being preferably provided with suitable stop shoulders for any standard 25 draft rigging. A cover plate 14 is applied to the top of the casting A, said plate extending from the buffing or striking plate or casting 15 to a point inwardly of the king pin opening in the center plate 10, as clearly 30 shown in Figs. 2 and 3. The striking casting 15 is also preferably formed integrally with the casting A. As appears from an inspection of Fig. 3, the laterally extended arms 11 of the casting A terminate approximately midway between the longitudinal 35 center of the car and a plane coincident with the extreme outer side of the car and the end of each of said arms 11 is formed with a diagonally extending wide flange 16. In lieu of the usual center sills, I provide what may be termed side sills, the same being shown as of channel formation at 17. Each of said side sills 17 is riveted at its end to an integral flange section 40 18 of the combined bolster or casting A and striking plate 15. From its end at 18, the side sill extends diagonally across the flange 16 of the corresponding arm 11 of the casting A and to which it is riveted and thence 45 to a point indicated at 19 at the outside of the car and from the point 19 the side sill extends longitudinally or parallel to the center line of the car when it is bent inwardly at the opposite end of the car. What may be 50 termed auxiliary side or longitudinal sills 55 are employed, one on each side of the car, the same being indicated at 20. As shown, each sill or strength member 20 is of angle form (see Fig. 5), the ends thereof being attached to the arms 11 of the casting A and 60 paralleling the corresponding portions of the outer or main sills 17, as shown in Fig. 3. Suitable gussets 121—122 are employed to strengthen the connections between the 65 various parts at the end of the car.

With the underframe construction just described, it is evident that buffing shocks and draft shocks will be distributed diagonally to the sides of the car and taken up in large part by the sills 17 and 20. In this construction, the casting A, in so far as the bolster proper thereof is concerned, acts as a strut between the diagonally extending portions of the sills 17 and 20 with consequent increase in strength for the car underframe as 70 compared with the usual arrangement of bolster where the buffing and pulling shocks are transmitted thereto merely at the center in line with the draft rigging and at points at the ends of a bolster of the full width of 80 the car. The other parts of the car framing, including the body bolsters, which are utilized to carry the shocks will be described hereinafter.

The single hopper employed in carrying 85 out my invention is of peculiar construction and designed to obtain the maximum capacity combined with the feature of quick self-clearing of the ore. As shown, the hopper is defined by two side hopper walls B—B 90 and two end hopper walls C—C.

Each side wall B has the upper portion thereof extending in a vertical plane and each defines the upper portion of the side wall of the car itself. Said vertical section 95 of each side wall B is designated by the reference 21 and has an upper horizontally extending edge 22, a lower parallel horizontally extending edge 23 and symmetrically arranged diagonally extending edges 24—24 100 as shown most clearly in Fig. 2, so that said vertical portions of the side walls are deeper between the trucks than over the trucks. Below the lines indicated at 23 and 24, each hopper side wall B is sloped or inclined inwardly toward the center of the car at an angle of approximately 64° to the horizontal, the central section of said inclined portion being indicated at 25 and the triangular end-shaped sections thereof being indicated at 110 26. The lower edges of the inclined sections 25 and 26 are indicated by the references 27 and 28 respectively. The side walls are braced by top longitudinally extending bulb angles 29 and built-up side stakes or posts 115 30—30. Below the line 27, indicated in Fig. 2, the side hopper wall is extended vertically for a short distance as indicated at 31 where it is secured to the sill 20.

Each end hopper wall C of the car slopes 120 in a general downward direction toward the middle of the car, as shown in Fig. 2. At its top edge indicated at 32, each end wall C is made flat and of the full or maximum width of the car. By this means I obtain 125 an unobstructed rectangular open top of maximum dimensions for the top of the car to thereby facilitate loading. The end wall is suitably braced by an angle iron 33, the side and end walls of the hopper being 130

strengthened by gussets 34. Each end hopper wall C, from its upper edge 32 is formed with the center of gradually increasing depth toward the bottom, the lowermost 5 lines of the end hopper wall so formed being indicated by the reference 35 and in fact corresponding to the section of the end hopper wall C as shown in Fig. 2. This construction I obtain by gradually changing 10 the form of the end hopper wall C from that of a flat section at the top to one of gradually increasing curvature toward the bottom, the bottom edge having the shortest radius. By so forming the end hopper 15 walls C, I am enabled to materially increase the capacity of the car since the lowermost part of the end wall as indicated by the line 35 may be dropped down below the level of the underframe proper, inasmuch as it 20 is between the walls and side frames of the truck and there is ample clearance, therefore, to accommodate the swiveling movements of the trucks. The side edge portions 25 of the end hopper wall C, indicated at 25 36 (see Figs. 5 and 6) are bent to an angle corresponding with the sloping sections 25 and 26 of the side hopper walls B and united thereto by rivets which are preferably countersunk on the inside of the hopper. The inclined or sloping portions 36 of the hopper end walls are merged with the main portions thereof by curved bends 30 of relatively short radius as indicated at 37. With the construction described, it will 35 be observed that, in plan view, the hopper end walls C become gradually narrowed toward their lower ends on account of the merging of the side portions of the end walls with the side walls B as the positions 40 of the latter change from vertical to inclined. With this construction, not only is the proper slope of the end walls and side walls of the hopper maintained from top to bottom but the gradual contraction or 45 tapering of the hopper as an entirety from top to bottom is effected without producing any shoulders or projections or abruptly restricted passage such as have heretofore been common in cars of the ore type. By 50 employing the arrangement shown and described, the discharge of the ore is effected rapidly and without danger of the load becoming bridged or rigid while the car is being emptied. Furthermore, by maintaining 55 the greater part of the side walls B vertically, I avoid cutting out any unnecessary amount of load-carrying capacity while obtaining the necessary structure to apply the hopper doors and maintain them within the 60 over-all width of the car. It will also be noted from an inspection of Fig. 1, that another feature which enables me to obtain the maximum capacity mentioned, resides in the fact that the top edges of the upper ends of 65 the hopper are extended substantially over

the axles of the end sets of wheels or, in other words, to points where there is left merely sufficient space to accommodate the hand brake within vertical planes corresponding to the extreme end faces of the 70 striking plates.

Each hopper end wall C is suitably braced intermediate its top and bottom edges by a transversely extending angle 39. Other strengthening angles 40-40 are employed 75 extending lengthwise of the hopper end wall C as clearly shown in the drawings. In the case of all of the angles 39, and 40, the flanges thereof which are secured to the sheets defining the end walls C are preferably united by spot welding so as to avoid any possible interference with the easy passage of the load down the walls C.

With the arrangement of side and end hopper walls described, I obtain a single 85 discharge opening which is of substantially square formation in plan view and in actual practice the size of this opening in plan, will be six feet six inches square. To close the discharge opening, I employ two hopper 90 doors D-D of like construction. Each door D is hinged along its upper outer edge by hinge butts 41 preferably secured to the auxiliary side sill 20. The normal position of the doors D is generally downwardly 95 sloping toward the center line of the car as indicated in Fig. 7, each door being preferably curved to conform to the contour of the lower edges 42 of the end walls C. Each door D is braced on its under side by 100 channel shaped pressings 43 and by a longitudinally extending channel shaped bar 44, the ends of the latter as indicated at 45 in Figs. 1 and 2 projecting beyond the ends of the door in order to provide means of attachment for the operating mechanism hereinafter described. The bars 44 are so placed 105 that they will engage the rails 46 when the doors are opened, as indicated in Fig. 7 and thereby insure the discharge of all of the 110 material to points within the rails and into the bins.

It is desirable to provide wings or baffle plates at the ends of the hopper opening in order to insure discharge of the load within 115 the bins and furthermore it is desirable to reinforce the lower edges of the end hopper wall C so as to prevent injury thereto as the load is discharged. To accomplish these two results, I have provided a novel form 120 of member shown detached in Fig. 8 and illustrated also most clearly in Figs. 1, 2 and 7. Each of said members, referenced 38, preferably consists of a unitary structure in the form of a pressed plate, the 125 same being curved throughout its length to conform to the curvature of the lower part of the end wall C. At the center of the car, the section of said member 38 is substantially channel shaped as indicated at 130

90. The upper flange 91 of said channel section is continued to points adjacent the auxiliary sills 20 as indicated at 92 in Figs. 5 and 8. The lower flange 93 of the member 38 is continued to the points indicated at 94 in Figs. 5 and 8 and outwardly thereof, the member 38 is provided with a depending sheet or flange 47 which acts as the baffle or wing to prevent spreading of 10 the load as it is being discharged. The flanges or wings 47 are reinforced along their inclined edges by flanges 95 and 96 integral therewith. At each end, the member 38 is secured to the main side sills as 15 indicated at 97. In this manner the member 38 performs the additional function of a needle beam or cross girder for the under-frame, thereby materially strengthening the latter, particularly against collapse or buckling. The rivets which secure the member 20 38 to the end wall C are also preferably countersunk on the inner side to avoid interference with the discharge of the load. The member just described in detail adds 25 great strength to the car sills providing the baffles or wing plates to control the discharge.

The mechanism for operating the doors D is preferably constructed as follows: At one 30 end of the car above the underframe structure and beneath the corresponding hopper end wall C, a transversely extending shaft 48 is employed, the same extending from side to side of the car so that it may be operated from either end. This shaft carries ratchet wheels 49-49 at both ends and adapted to coöperate therewith are locking dogs 50-50 rigidly mounted on a common transversely extending shaft 51. Coöper- 35 able with the dogs 50 are cams 52-52 rigidly mounted on the ends of a common transversely extending shaft 53. Each of the shafts 48, 51 and 53, has means at the ends thereof to receive a claw bar or other 40 suitable similar tool so that the operating mechanism can be actuated or released from either side of the car. The various shafts are suitably journaled in bearing brackets carried by upright angles 54 and plates 55. 45 At the opposite end of the car, a second transversely extending shaft 56 is employed similarly located as the shaft 48 but in this case extending only slightly more than half way across the car. The shafts 48 and 56 50 carry sprocket gears over each of which passes a section of sprocket chain 57. The ends of the sprocket chains 57 are connected to long heavy links 58 and 59, one of said links—as for instance the link 58 being bifurcated so as to permit the passage there- 55 through of the other link 59. With this construction, it is evident that upon clockwise rotation of the shaft 48, the other shaft 56 will be simultaneously rotated but in a coun- 60 ter-clockwise direction. The links 58 and 65

59 and sprocket chains, etc., are accommodated in the triangular space provided beneath the adjacent sloping section 25 of a side wall B and a vertically extending combined cover and strength car side wall plate 70 75 60. Triangular reinforcing steel pressings 61 are employed in this triangular space, the same being secured to the car side plates 60 and the sloping hopper side sections 25 and to the tops of the side sills 17 and 20. 75 Those pressings 61 on the side of the car where the links 58 and 59 are found, are cut away as indicated at 62 to accommodate said links and chains, as indicated in Fig. 7.

Between each of the shafts 48 and 56 80 and the corresponding extended ends 45 of the bars 44 is interposed a preferably self-locking flexible linkage constructed as follows: On each shaft is rigidly secured a hub 63 to which is pivoted a short link 64, 85 the latter having pivoted thereto a heavy link 65 with oppositely and laterally extended arms 66. To each of the arms 66 is pivotally connected an elongated hook-shaped link 67, each link 67 at its lower end 90 having an adjustable eye-bolt 68 secured thereto, the bolts being in turn connected by the links 69 to the extended arms 45 of the bars 44. The hook-shaped links 67 in combination with the link 65 seat upon the drum 95 63 in such a way as to eliminate torsion on the shaft when the parts are in position corresponding to the doors closed, in a well known manner. With the arrangement shown, it is evident that the doors may be 100 opened and closed from either side of the car by manipulating the shaft 48.

To properly sustain the end portions of the hopper, complete the body holsters, and utilize the sides of the car as load carrying 105 members, I employ the following construction: Secured to the tops of the sills 17 and 20 and the flanges 12 of the casting A are plates 70, one on each side of the car, at each end thereof, as indicated in Fig. 3. 110 These plates are preferably provided with an opening 71 to prevent accumulation of dirt or other foreign matter in the pockets formed at these points on the car. Extending upwardly from the casting A, on each side thereof is a plate 72, the inner edge of each plate 72 being connected to a vertically extending angle 73. The outer edges of the plates 72 are riveted to angles and plates 74 which extend upwardly and outwardly 115 to points in line with the sides of the car and are then carried upwardly vertically to the top of the car, as shown in Figs. 4 and 6. At each end of the car and on each side of the center line thereof, a vertically ex- 120 tending longitudinal plate 75 is employed, the same being flanged at its lower edge and riveted to the corresponding horizontal plate 70. Each plate 75 is of substantially triangular form, the vertical edge thereof be- 125 130

ing united to the angle 73 and the inclined edge being united to the angle 40. Inclined braces 76 are employed extending from the striking plate to the outer end wall C and 5 united to corresponding angle irons 40 as shown in Fig. 2. Additional braces 190—190 are preferably used, the same extending from the striking plate to the upper edge of the end wall C as shown in Figs. 1, 2 and 4; and 10 also inclined braces 191—191 as shown in Figs. 4 and 6.

From the immediately preceding description, it will be seen that the elements 72, 73, 15 74 and 75 constitute parts of the bolsters and serve to increase the width of the bolsters in their upper portions to the full width of the car. In this way, not only are the ends of the hopper properly supported but the loads from the bolsters are transmitted 20 efficiently to the side walls of the car and said walls utilized as strength load-carrying members.

It will be noted from the drawings that I provide four ladders, one at each corner 25 of the car. To carry out this construction, at each corner of the car I provide laterally extended supporting angles 77 and 78 and vertically extending angle iron stiles 79 and 80, the latter going to the top of the car and 30 the former uniting with a side stake or brace as indicated at 81. A step 82 and rungs 83 are secured to the stiles and it will be noted that the ladder thus formed is in a plane flush with the side wall proper of the car, 35 thus avoiding any increased over-all width and providing ample room for the feet and hands of the brakeman in conformity with the safety laws. In the latter connection, it will be noted that the upper rung 84 of the 40 ladder comes opposite the vertical portion of a side wall and in order that the necessary clearance may be obtained at this particular point, the side wall will have a depression 85 therein as indicated in Fig. 1. Suitable 45 platforms 185 are provided at each end of the car extending the full width thereof and supported on brackets 86 secured to the corner stiles 80 and a transversely extending angle iron 87 similarly supported. Grab 50 irons are provided as indicated at 88. A hand brake is indicated conventionally at 89, it being noted that the latter is disposed inside of a vertical plane corresponding to 55 the outer face of the striking plate 15.

Although I have herein shown and described what I now consider the preferred manner of carrying out the invention, the same is merely by way of description and not by way of limitation. All changes and 60 modifications are contemplated that come within the scope of the claims appended hereto.

I claim:

1. As an article of manufacture, an end 65 wall for a hopper ore car, said end wall comprising a main central portion with a straight upper cross edge corresponding to the maximum width of the hopper, said main portion gradually changing to a curved section at the bottom thereof with said 70 curved section of gradually increasing depth and curvature from the top to the bottom, said end wall having also side edges inclined upwardly and outwardly and merged with said main central portion by curved 75 bends of short radius.

2. In a single hopper ore car, the combination with opposed side hopper walls, each having the upper portion thereof extending vertically and the lower portion sloping 80 inwardly toward the center of the car, said upper portion having the top and bottom edges thereof extending parallel and the ends defined by inclined lines, the upper points of said lines terminating at the corners of the car, the upper edge of each said side wall being of a length equal to the distance between the axles of the end sets of car wheels; of end hopper walls, each sloping in a generally downward direction 85 from the top of the car toward the middle thereof, each said end wall being flat across the top and provided with a central portion of gradually increasing depth and curvature from said top flat edge to the bottom of the 90 wall, the side portions of each end wall merging with the adjacent vertical and sloping portions of the side walls, the lower edges of the side and bottom hopper walls defining a discharge opening disposed centrally of 100 the car between the trucks; doors for closing said opening; and mechanism for operating said doors.

3. In a single hopper ore car, the combination with opposite side hopper walls, each 105 side hopper wall having the upper part thereof extending in a vertical plane and the lower part thereof extending in a plane inclined downwardly toward the center of the car; of end hopper walls, each sloping downwardly from the top edge of the car to a point between the trucks, each of said end hopper walls being flat at the top and gradually changing to a curved section of varying radii and with the shortest radius at the 110 bottom thereof, the side portions of said end hopper walls merging with the adjacent vertical and sloping portions of the side hopper walls, the lower edges of the side and end hopper walls defining the discharge 115 opening; doors for closing said opening, and mechanism for operating said doors.

4. In a hopper car, the combination with side hopper walls; of end hopper walls, each end hopper wall sloping downwardly from 120 the top of the car and of a section gradually changing from flat to curved and with the curvature of minimum radius at the bottom thereof, the lower edges of said side and end hopper wall defining a single, unob- 125

structed discharge opening; means for closing said opening; and mechanism for operating said means.

5. In a hopper car, the combination with 5 side hopper walls; of end hopper walls, each end hopper wall sloping downwardly from the top of the car and of a section gradually changing from flat to curved and with the curvature of minimum radius at the bottom 10 thereof, the lower edges of said side and end hopper wall defining a single, unobstructed discharge opening; a pair of oppositely swinging doors for closing said opening and having their free edges meeting 15 centrally of the car, each of said doors being curved to correspond with the curvature of the lower edges of said end hopper walls; and mechanism for operating said doors.

6. In a car of the character described, the 20 combination with a hopper having side and end walls converging downwardly, the lower edges of said end walls having the central portions thereof lower than the side portions; of doors for closing the hopper opening; mechanism for operating said doors; and a reinforcing member secured to the 25 under side of each hopper end wall at and conforming to the contour of the lower edge thereof, each reinforcing member extending 30 from side to side of the hopper end wall and being provided at its ends with integrally formed depending wings adapted to serve as baffles.

7. In a car of the character described, the combination with a hopper having side 35 and end walls, the latter being curved at their bottom edges; of doors for closing the hopper opening; mechanism for operating the doors; an underframe including side sills located outside of the lower edges of 40 said hopper end walls; and a reinforcing, combined cross brace and baffle member secured to the underside of each said curved end wall, said member extending from side sill to side sill and secured at its ends there- 45 to, the top of said member conforming to the curvature of the end wall where attached thereto, said member having depending wings near each end thereof adapted to serves as baffles. 50

8. As an article of manufacture, a combined cross brace and baffle member for a hopper car, said member having an arcuate top edge and depending wings near each end thereof, said member being flanged at 55 its ends and along its top edge to thereby adapt it to be secured to a hopper sheet and longitudinally extending sills of a car under-frame.

In witness that I claim the foregoing I 60 have hereunto subscribed my name this 22nd day of June, 1920.

ARGYLE CAMPBELL.
